UNITED STATES PATENT OFFICE.

JOSEPH BERGER, JR., OF UTICA, NEW YORK, ASSIGNOR TO UNION SPECIAL MACHINE COMPANY, OF CHICAGO, ILLINOIS, A CORPORATION OF ILLINOIS.

SEWING-MACHINE

1,856,334.

Specification of Letters Patent.

Patented Oct. 19, 1920.

Application filed July 20, 1915. Serial No. 40,895.

To all whom it may concern:

Be it known that I, JOSEPH BERGER, Jr., a citizen of the United States, residing at Utica, in the county of Oneida, State of 5 New York, have invented certain new and useful Improvements in Sewing-Machines, of which the following is a description, reference being had to the accompanying drawing and to the figures of reference marked 10 thereon.

The invention relates to new and useful improvements in sewing machines and more particularly to a sewing machine adapted to make a flat seam for covering or joining 15 the edges of fabric.

An object of the invention is to provide a sewing machine of the above character having a standard and an overhanging arm supporting the needles and cross stitching mechanism, with a supporting arm which is carried by the standard and which projects outwardly and upwardly from the standard and carries a depending portion which supports at its lower end the work supporting 20 arm proper, whereby small tubular articles may be formed about said work supporting arm and fed off from the end thereof as they are stitched.

A further object of the invention is to 30 provide a sewing machine for forming a flat seam with stitching mechanism which comprises in effect two independent sets of stitching mechanism, one operating in the rear of the other, and so arranged that each 35 forms parallel rows of connected needle loops, the needle loops and connecting threads formed by one stitching mechanism overlying in part or in whole the needle loops and connecting threads formed by the other 40 stitch forming mechanism.

A further object of the invention is to provide means for guiding the edges of two sections of a fabric to be joined or covered, so that the edges of said sections meet substantially midway between the outer needles 45 of the stitch forming mechanisms.

A still further object of the invention is to provide means for trimming the edges of two sections of a fabric to be joined prior to 50 the joining or covering of the same by the stitching mechanism.

A still further object of the invention is to provide a stitching mechanism of the above character which consists of two sets of 55 spaced needles, one set being arranged and

operating in the rear of the other with separate complemental stitch forming mechanism for each set of needles.

A still further object of the invention is to provide a stitching mechanism of the above 60 character with separate thread laying devices above the fabric for each set of needles.

These and other objects will in part be obvious and will in part be hereinafter more 65 disclosed.

In the drawings which show by way of illustration one embodiment of the invention—

Fig. 38 is a top plan view showing the seam made by this stitch forming mecha- 70 nism.

General structure.

The invention consists generally in a sewing machine having a supporting standard 75 which carries an overhanging arm in which reciprocates the needle bar carrying the needles. The operating shaft for the machine is located in the standard. Also mounted in the standard and extending outwardly 80 and upwardly therefrom is a supporting arm and this supporting arm at its free end carries a horizontal arm which is parallel with the overhanging arm of the machine and it is also raised above the plan of the 85 base of the machine, so that an operator may readily reach beneath said horizontal arm. The horizontal arm at its free end carries a depending arm and this depending arm at its lower end carries the work sup- 90 porting arm proper of the machine which is preferably cylindrical in cross section. This work supporting arm projects toward the overhanging arm and the free end thereof is substantially beneath the free end 95 of the overhanging arm, so that the looper mechanism which coöperates with the needles may be located in this arm. The horizontal arm carries a rotating shaft which is operated from the main shaft in the stand- 100 ard and the loopers are operated from the rotating shaft in the horizontal arm. Also located in the work supporting arm is a differential feeding mechanism which is op- 105 erated by suitable mechanism from the rotating shaft in the horizontal arm. A trimmer is carried by the overhanging arm and operates to prepare the fabric edges for the stitching mechanism. The fabric has its edges brought together on the upper 110 side of the work supporting arm and the feeding mechanism operates to feed the joined edges off from the arm. The said edges are fed to the trimming mechanism where they are trimmed and they are then 115 brought into abutted relation to each other and joined by the stitching mechanism.

The stitching mechanism consists of two pairs of spaced needles, one pair being in rear of the other. There is a looper for 120 each pair of needles within the work supporting arm and thread laying devices for each pair of needles carried by the overhanging arm, so that the stitching mecha- 125 nism forms in effect two independent lines of needle loops which are connected above and below the fabric, and these pairs of needles are so arranged that the connecting threads of the needle loops of one pair of needles overlie in part or in whole the con- 130

necting threads of the needle loops of the other set of needles.

Work supporting mechanism.

- 5 Referring more in detail to the drawings, my improved sewing machine consists of a standard 1, which is carried by a supporting base 2. On this standard is mounted an overhanging arm 3. Within the standard 10 1 is the main operating shaft 4, which is operated by a belt wheel 5. Projecting outwardly and upwardly from the standard is a hollow arm 6. This hollow arm 6 at its outer end supports a horizontal arm 7. The 15 horizontal arm 7 is substantially parallel to the overhanging arm 3. As shown in the drawings, the arm 6, projects outwardly in a plane substantially at right angles to a plane containing the overhanging arm 3. 20 The horizontal arm 7 at its free end carries a depending arm 8, the depending arm at its lower end carrying the cylindrical work supporting arm 9. This cylindrical work supporting arm 9 projects forwardly from 25 the depending arm 8 to a point substantially underneath the free end of the overhanging arm 3.

My machine is especially adapted for stitching the edges of fabric to form tubular articles. The fabric having the edges to be joined is placed underneath the cylindrical work supporting arm 9 and the edges are brought up around each side of the arm until they meet at the upper side of said arm. 35 The horizontal arm 7 is located some distance above the base 2, or the table on which said base rests, and this affords a space for the arm of the operator so that the fabric may be readily placed around the cylindrical work supporting arm 9 and properly guided to the stitch forming mechanism. 40

Stitch forming mechanism.

At the forward end of the overhanging arm 3 is a supporting head 10 in which reciprocates a needle bar 11 carrying, as herein shown, four needles. The needles 12 and 13 form one pair of needles, while the needles 14 and 15 form another pair. The 45 needle bar 11 is reciprocated by a needle lever 16 which is pivoted at 17 to the overhanging arm and is oscillated by a link 18 coöperating with an eccentric on the main shaft 4. The needle lever at its outer end 50 is connected by a link 19 with the needle bar 11.

Coöperating with the needles 12 and 13 within the work supporting arm is a complementary stitch forming mechanism, which, 55 as herein shown, has a single looper 20. Also coöperating with the pair of needles 14 and 15 is a single looper 21. The looper 20 is mounted in a looper carrying head 22 which is formed integral with a looper supporting shaft 23 and the looper supporting

shaft 23 is mounted to oscillate in suitable bearings 24 and 25 located within the work supporting arm. The looper carrying head 22, as clearly shown in Fig. 23, has a projecting stud 26, on which is clamped an auxiliary looper carrier 27. The looper 21 is mounted in a suitable socket 28 in the carrier 27, while the looper 20 is mounted in a suitable socket 29 in the looper carrier 22, and is locked in position by a set screw 70 20 which extends through the stud 26. The looper carrier 22 is cut away, as at 30, to form a clearance space for the needles. This construction permits either looper to be removed without affecting the other looper, 75 and also permits of the looper being successively adjusted relative to the respective pairs of needles. The carrier 27 can be moved about and along the stud 26.

As above noted there is a separate looper 80 which coöperates with each pair of needles, and, therefore, the needle loops of one pair of needles will be joined beneath the material by a looper thread which serves not only to lock the needle loops but also to connect 85 the needle loops across the meeting edges of the sections of fabric to be joined, as will be hereinafter more fully disclosed.

The looper shaft 23 extends lengthwise of the work supporting arm to a point within 90 the lower end of the depending arm 8. A shaft 31 is mounted to rotate in suitable bearings in the horizontal arm 7. This shaft is connected by two operating links 32 and 33 with the main shaft 4. On said main shaft 4 are two staggered cranks, while the shaft 31 also has two staggered cranks, and, therefore, these links will operate to impart a positive rotation to the shaft 31 from the shaft 4. On the outer end of 95 the shaft 31 is a crank pin 34 to which is connected a link 35. This link 35 at its lower end is pivoted to a crank arm 36 rigid with the end of the looper shaft 23. The said link 35 is pivoted to a rod 37 at 100 38 and this rod 37 slides in a sleeve 39 which sleeve is mounted on an oscillating support 40. The axis of the oscillating support 40 is at right angles to the plane of movement 105 of the rod 37. As the link 35 moves up and down, this rod becomes a movable fulcrum for the link 35 and in effect converts the link into a lever fulcrumed between its ends, so that the link 35 imparts not only an oscillating movement to the looper supporting 110 shaft 23, but also an endwise movement thereto. The loopers are by this mechanism moved into their needle loops, then given a sidewise or lateral needle avoiding movement, after which they are retracted to shed 115 their needle loops and then again moved laterally for entry of the next needle loops. This looper mechanism *per se* forms no part 120 of the invention and further description thereof is not thought necessary.

At the lower end of the needle bar 11 is a needle clamp for supporting and positioning the needles. Said needle clamp consists of a needle head 41, which is clamped to the lower end of the needle bar 11. The needle 12 is mounted in said needle head and held therein by a set screw 42, see Figs. 24 to 29. The needle 13 is located in the lower end of the needle bar and is held therein by a set screw 43. The needle 13 has its point raised above the point of the needle 12, as in the well known manner where the needles are widely spaced and a single looper co-operates with both needles. The needle 14 of the rear 15 pair of needles is mounted in the needle head 41 and is held therein by a set screw 44. Directly above the needle head 41 is a collar 45 which is also secured to the needle bar and this collar serves as a stop for vertically positioning the needle 14. The needle 15 is also carried by the needle head 41 and a set screw 46 holds the same in place. A projecting lug 47 on the collar 45 determines the vertical position of this needle 15. Said needle 15 is set with its point somewhat above the needle 14, for reasons above stated.

As clearly shown in Figs. 17 to 19, inclusive, each pair of needles has separate thread laying devices co-operating with the same above the fabric. In Fig. 17, the fabric is indicated at F. The meeting edges of the two sections of fabric to be joined are indicated at f. A thread *a* is guided by a thread guiding finger 48 and the thread is laid back and forth so as to be stitched to the fabric by the needle threads carried by the respective needles 12 and 13. A second thread *b* is carried by a thread guiding finger 49 and this thread is laid back and forth on the upper face of the fabric and joined thereto by the threads of the respective needles 14 and 15. The thread fingers 48 and 49 have a movement in a direction substantially parallel with the line of feed. Co-operating with the thread finger 48 is a thread hook 50, while a thread hook 51 co-operates with the thread finger 49. The thread fingers 48 and 49 are brought to the position shown in Fig. 17, and then the thread hooks move forward, as shown in Fig. 18, engaging the threads *a* and *b*, respectively, and forming loops, as shown in Fig. 19, between the strands of which the respective needles 12 and 14 pass, the threads of course passing under the raised needles 13 and 15.

These thread hooks 50 and 51 are carried by an arm 52. Said hooks are adjustably fixed to the arm for lateral and vertical adjustments, and said arm is pivoted at 53 between suitable spaced supporting lugs projecting from a bracket 54 which is attached to the supporting head on the overhanging arm. The pivotal point 53 is considerably in rear of the needle bar. The thread hooks

are fixed to the arm 52 and are so positioned that, when the arm swings about the pivotal point 53 the hook 50 will pass in front of the needles 12 and 13, while the hook 51 passes between the pairs of needles—that is, in rear of the needles 12 and 13 and in front of the needles 14 and 15. The arm 52, as herein shown, is integral with an arm 55. At the rear of the machine, as clearly shown in Fig. 2, there is a rock shaft 56 which is mounted to oscillate in bearings 57 and 58. This shaft 56 is oscillated by a link 59 which co-operates with an eccentric on the main shaft 14, see Fig. 4. Loosely mounted on the shaft 56, but held from endwise movement thereon, is a sleeve 60. This sleeve carries a downwardly projecting arm 61, which is pivoted at its lower end to a link 62, see Fig. 13, and this link 62 is in turn pivoted to an arm 63 telescoping within the arm 55 and clamped therein by a screw 64. Also mounted on the shaft 56 is a second sleeve 65, which is likewise loose on the shaft, but held from endwise movement thereon. In other words, the shaft 56 is merely a bearing support for the sleeves 60 and 65 and the movement of the shaft 66 is in no wise imparted to these sleeves. The sleeve 65 has a forwardly projecting arm 67, see Fig. 1. This arm at its outer end is pivoted to a link 68, which in turn is pivoted to a ball stud fixed at 69 to the needle lever 16. This ball stud is on the rear face of the needle lever and the overhanging arm is provided with a recess 70 to permit free oscillation of the needle lever. As the needle lever oscillates, the sleeve 65 will be oscillated on the supporting shaft 56 therefor. The sleeve 65 has a second arm 71, which projects downwardly therefrom, while the sleeve 60 likewise has a downwardly projecting arm 72. The arm 71 carries a spring-pressed plunger 73, see Figs. 15 and 16. This plunger is formed with a hand-piece 74 and a spring 75 is housed in the arm 71 which normally forces the plunger toward the arm 72. The arm 72 is formed with a tapered recess 73^a to receive the tapered end of the plunger, thus providing means for taking up any wear and thereby prevent any loose movement. Said arm is also formed with laterally projecting spaced ribs 76—76. The purpose of this detachable connection between the arms 71 and 72 is to permit the sleeve 60 to be disconnected from its oscillating mechanism, so that the thread hooks, oscillated by this sleeve may be moved to a limited distance away from the needles. This is for the purpose of giving access to the needles for threading or renewing. If the machine should be started with these parts disconnected, the arm 71 will be rocked and the spring plunger will be forced into the socket or opening in the arm 72 as soon as it comes 130

into register with the plunger and, therefore, the parts will be automatically connected on the starting of the machine.

The thread fingers 48 and 49 are carried 5 at the lower end of a lever 76' and are held in place by suitable clamping means. The lever 76' is pivoted to a bracket arm 77 at its lower end and this bracket arm 77 may be formed as a part of the bracket 54 which 10 supports the thread hooks. Said lever 76' is connected to a link 78 and this link 78 is in turn connected to a downwardly projecting arm 79, see Fig. 3, mounted on the cross shaft 56. As the cross shaft 56 oscillates 15 the arm 79 will be moved back and forth and this will swing the lever 76' in a plane substantially parallel with the line of feed. The thread fingers, therefore, move in a direction substantially at right angles to the 20 direction of movement of the thread hooks and this enables the threads carried by the guiding fingers to be properly positioned for the thread hooks and also to coöperate with the thread hooks in properly laying 25 the cross threads relative to the needles.

The threads for the needles are led from the supply through suitable tensions T mounted on a bracket 80 and thence through 30 guides to the needles. The threads are not shown in the drawings. The tensions may be released by a suitable releasing arm 81, which is operated from the presser foot lifting mechanism.

In Figs. 33 to 38 inclusive I have shown 35 a modified form of stitch forming mechanism. In this form of the invention the needles 12^a and 13^a forming the front pair of needles are widely spaced while the needles 14^a and 15^a which form the rear pair 40 of needles are comparatively closely spaced. Each of the rear pair of needles is set in a line which is parallel of the line of feed and passes between the front pair of needles.

Coöoperating with the needles 12^a and 13^a 45 beneath the work support is a looper 20^a while a looper 21^a coöperates with the rear pair of needles 14^a and 15^a.

The needles 14^a and 15^a being very 50 closely spaced are also provided with a loop retainer 21^b. This loop retainer has a projecting finger 21^c which is adapted to coöperate with the looper 21^a and hold the needle loops formed in the threads of the needles 14^a and 15^a spaced as shown 55 in Fig. 34, which permits the needle 15^a to pass between the needle loops. This loop retainer is of the well known construction and further description thereof is not thought necessary. Said loop retainer is 60 mounted in the bearing support on the front end of the work supporting arm 9.

The loopers 20^a and 21^a are mounted in the same manner as above described in connection with Figs. 5 and 23.

The thread laying devices are also of the 65 same construction as those above described and have been similarly numbered.

In Figs. 36 and 37 I have shown more in detail the clamp for the needles, which consists of a supporting needle head 41^a and a 70 positioning collar 45^a. These parts operate in precisely the same manner as described in connection with Figs. 24 to 29 inclusive.

Trimming mechanism.

75

The sections of fabric F, as clearly shown in Fig. 17, when joined have their edges abutted, so as to make a flat seam. In order to prepare the edges, so that they may be abutted, I have provided a trimming mechanism which consists of a stationary trimming blade 82 and an oscillating trimming blade 83. The oscillating trimming blade is clamped to an arm 84. This arm 84 is in turn clamped to an extended bearing 85 on the lower end of the yoke 86, see Fig. 32. This yoke 86 is mounted on the presser bar so as to oscillate about the axis of the presser bar. Said yoke has two spaced bearings through which the presser bar passes and one of the arms is connected to this extended bearing 85. A spring 87 surrounds the presser bar and forces the yoke downward along said presser bar so as to hold the movable trimmer blade in shearing contact with the stationary trimming blade 82. Said movable blade has a projecting part at the rear side thereof which continuously overlaps the stationary blade. The yoke 86 has a forwardly projecting arm 88 which carries a ball stud which is pivotally connected to a link 89, see Fig. 4. This link 89 is pivoted at 90 to a rock lever 91 which is mounted on a suitable bracket 92 carried by the standard. The other arm of the rock lever is pivoted to a link 93 which in turn is pivoted to a ball stud 94 carried by the needle lever. As the needle lever is oscillated the link 89 will impart oscillations to the yoke 86 and this will in turn oscillate the movable trimming blade. The movable trimming blade 82 is carried by the presser foot and, therefore, both members of the trimming mechanism will move up and down with the presser foot and without increasing the pressure of the movable blade against the stationary blade.

The edges to be trimmed are fed in a vertical position between the stationary and movable trimmer and after the edges are trimmed said edges are abutted and directed to the stitching mechanism. The trimmed off strip is guided away from the stitching mechanism by a strip deflector. This strip deflector is provided with a fixed section 96 which is secured to the presser foot and spans the slot through which the edges of the fabric are guided. A section

97 is carried by a movable arm 98 which is pivoted to a lug 99 on the presser foot. A spring 100 carried by the arm 98 bears against a square shoulder on this lug 99 and serves to hold this movable section of the strip deflector in the full line position shown in Fig. 30 or in dotted line position shown in Fig. 13. The purpose of this movable section of the strip deflector is to give access to the needles for threading or renewing.

Presser foot mechanism.

The presser foot 101 is carried by the presser bar 102 on which the yoke 86, above described, is mounted. This presser bar is mounted to slide in the supporting head of the overhanging arm 3 and may be raised either by the hand lever or by a lever 104 which is connected to a suitable treadle. This presser foot has two needle openings 105 and 106. The needle opening 105 is for the needles 14 and 15, while the needle opening 106 is for the needles 12 and 13. There is a stitch tongue 107 carried by the presser foot and projecting into each needle opening. This stitch tongue extends between the needles and the threads *a* and *b* are laid across the respective stitch tongues and slide off from the same in a well known way.

The stationary trimmer 82 is mounted in a groove in the presser foot and is clamped therein by suitable mechanism. The presser foot is formed in two sections, a fixed section 108 and a yielding section 109, see Fig. 30. This yielding section moves bodily up and down at one side of the fixed section and a suitable spring 110 normally holds said yielding section on the fabric. There is a space between the sections 108 and 109 at the forward end which provides a guiding channel 111 for the upturned edges of the fabric sections which are to be trimmed. The fixed section 96 of the strip deflector is secured to the fixed section of the presser foot and merely rests against an upturned lug 112 on the movable section of the presser foot. This fixed section of the strip deflector is also spaced slightly above the movable section of the presser foot, so that said movable section may yield in an upward direction. The purpose of this movable section of the presser foot is to permit an edge having a cross seam, or of more than one thickness, to be properly held while it is being stitched to an edge of a single thickness passing beneath the presser foot.

Throat plate.

60 Directly beneath the presser foot and carried by the work supporting arm 9 is a throat plate 113. This throat plate is secured to the work supporting arm by suitable screws 114. Said throat plate is provided with feed slots 115 and with openings

for the needles. The openings 117 are for the needles 12 and 13 and the openings 116 are for the needles 14 and 15. Between the needle openings for each set of needles there is a stitch tongue 118. The needle openings 116 terminate in advance of the needle openings 117 so that there is a solid portion of the throat plate which supports the rear stitch tongue 118.

The looper threads which join the needle loops beneath the work support are laid across the respective stitch tongues and are fed off the ends of the same. It will be noted that these openings for the needles in the throat plate and also the openings in the presser foot are arranged so that the pairs of needles at the rear are slightly offset relative to the pair of needles in front, the opening 116 for needle 14 being disposed in a plane extending between the openings 117. This results in the formation of the seam shown in Fig. 17. The front needles form what might be called a separate and independent seam from that formed by the rear needles. The needle 13 enters the sections of fabric closer to the meeting edges *f* than the needle 12, and likewise the needle 14 enters on the other side of the meeting edges substantially the same distance from the meeting edges as the needle 13, while the needle 15 is on the other side and substantially the same distance from the meeting edges as the needle 12.

As above noted, the pairs of needles are positioned one in rear of the other, and there are independent coöperating elements for each pair of needles. The stitches formed by the needles 14 and 15 overlap the stitches formed by the needles 12 and 13 in part. The covering and joining stitches, therefore, have anchoring loops located at some distance back from the meeting edges and covering threads which cross the meeting edges and extend lengthwise of the meeting edges at points adjacent said meeting edges.

In Fig. 35 of the drawing I have shown a throat plate 113^a which is adapted for the stitching mechanism shown in Figs. 33 and 34. Said throat plate is also provided with an opening 116^a for the needles 12^a and 13^a and a stitch tongue 118^a carried by the throat plate projects between the needles into these openings. Said throat plate has an opening 117^a for the needles 14^a and 15^a and a stitch tongue 118^a carried by the throat plate projects into this needle opening. This rear stitch tongue may be omitted if desired.

Feeding mechanism.

The fabric sections to be joined are fed to the stitching mechanism by a feeding mechanism which consists of a main feed dog 119 and an auxiliary feed dog 120. The main feed dog is carried by a feed bar 121, 130

while the auxiliary feed dog is carried by a feed bar 122. The auxiliary feed dog has a groove and tongue connection with the auxiliary feed bar, as shown in Fig. 22, 5 and is connected thereto by a clamping screw 123. The main feed bar 121 is located in the work supporting arm 9 and extends substantially from end to end thereof. Said feed bar between its ends is pivoted to a 10 forked arm 124. Said arm is mounted on a sleeve 126 having an eccentrically positioned opening therethrough which receives the bearing pin 128. Said pin is locked to the work supporting arm by a screw 129. By 15 loosening this screw and turning the pin by a tool in the slot 130, the sleeve which is keyed to the pin can be rotated and thus the feed bar raised or lowered. The rear end of the main feed bar 121 is in the form of 20 a yoke having two arms 131 and 132, see Fig. 21. These arms straddle the looper shaft 23, which also passes through the forked arm 124. The arms 131 and 132 are pivoted to a lever 133. This lever engages 25 an eccentric 134 at its upper end and the eccentric 134 is carried by the rotating shaft 31 in the horizontal arm. This eccentric carries the crank pin 34 of the looper operating mechanism. The lever 133 is ful- 30 crumed on a pin 135. This pin is carried by a second lever 136 which is fulcrumed on a vertically adjustable pin 137 carried by the depending arm 8. The upper end of the lever 136 has a forked engagement* with a 35 block 138, which in turn cooperates with an eccentric 139, fixed on shaft 31, see Fig. 10. The pin 137 extends into a fulcrum block 140 which is adapted to have sliding engage- 40 ment in a slot in the lever 136. As the shaft 31 rotates the eccentric 134 will bodily raise and lower the lever 133, and the lever 136 which is connected thereto by the ful- 45 crum pin 135 will slide on the fulcrum block 140. The lever 136 will be oscillated by the eccentric 139 and this will give a back and forth movement to the lower end of the lever 133. The resulting movement imparted to the feed bar is, therefore, an up and 50 down movement and a longitudinal movement. In other words, the main feed dog will be raised into engagement with the fabric, will move forward to feed the fabric, will then drop from engagement with the fabric and be retracted for the next feeding 55 movement.

The bar 122 which carries the auxiliary feed dog 120 is slidably mounted in a groove or recess 142 in the main feed bar 121. The up and down movements, therefore, of the 60 main feed bar will be imparted to this auxiliary feed bar. Said auxiliary feed bar may be given a differential feeding movement relative to the main feed bar through the following mechanism. A link 65 143 is pivoted at 144 to the auxiliary feed

bar 122, see Fig. 5. The other end of this link is pivoted at 145 to a rock arm 146, which in turn is mounted at 147 in bearings carried by the work supporting arm 9. A link 148 is pivoted at 149 to a lug 150, carried by the main feed bar 121, and the other end of this link 148 is pivoted at 151 to a block which slides in a segmental groove 152 in the rock arm 146. By shifting the link 148, so as to vary the pivotal connection 70 of the link with the rock arm, the oscillation of the rock arm, due to the bodily movement of the link 148, traveling with the main feed bar, may be varied. The oscillations of the rock arm 146 are imparted through 75 the link 143 to the auxiliary feed bar. The link 148 is shifted by a hand lever 153 which is connected by a link 154 to said link 148. This hand lever is fulcrumed on the work supporting arm and at its rear end is connected to a stud 155 which projects through 80 a slot 156 in the arm of the machine. On the outer face of the work arm there is a serrated plate 157 which is secured to the arm by suitable screws 158. The stud 155 85 carries a hand piece 159 which is pressed by a spring 160 into contact with the serrated plate 157 and the serrations serve to lock the stud in an adjusted position. The hand piece, however, may be moved out of en- 90 gagement with the serrated plate and the lever shifted in order to vary the position of the link 148 and thus vary the stroke of the auxiliary feed dog.

It will be understood that there are suitable removable cover plates for various portions of the arms which contain the mechanisms for operating the looper and the feed, but these cover plates have not been described in detail. It will also be understood 100 that there are suitable thread controlling devices for the looper threads which are indicated generally at L and L' see Fig. 1. There is also a thread clamp for the looper thread indicated at C, this figure. 110

In Fig. 38 of the drawing I have shown two sections of fabric indicated at F which are joined by my improved seam made on the stitch forming mechanism shown in Figs. 33 to 35 inclusive. The front pair of 115 needles are indicated in this figure at 12^a and 13^a while the rear pair of needles are indicated at 14^a and 15^a. The cross thread a is laid back and forth about the needles 12^a and 13^a while the cross thread b is laid 120 back and forth about the needles 14^a and 15^a.

Operation.

In the operation of my machine, the fabric sections to be joined are guided underneath the horizontal arm 7, the operator reaching beneath the arm guides the sections of the article about the work supporting arm 9, so that the edges to be joined will be directed into the receiving channel 130

of the presser foot. The feeding mechanism operates upon these sections and presents the same first to the trimming mechanism, where the vertical edges are trimmed, 5 and thence to the stitching mechanism where said edges are abutted and joined by the stitching threads. The auxiliary feed dog is preferably so controlled as to operate upon the material at a slightly greater 10 speed than the main feed dog which gathers in the material sufficiently to prevent stretching the same when operating upon elastic or knit material. The edges after they are trimmed are first joined by the 15 needle threads of the needles 12 and 13, together with the connecting threads, which, as described above, consists of the looper thread below and the cross thread above. After the edges have been joined, they are 20 then presented to the second pair of needles where the edges are again joined by the needle threads together with the connecting looper thread and cross thread and this pair of needles is so positioned that the 25 resulting lines of stitching overlap, that is, the cross thread and looper thread of the rear pair of needles, overlie in part or wholly and thus overlap the looper thread and cross thread of the front pair of needles 30 and thereby forms a very strong and durable flat seam which connects and covers the edges of the material.

The shaft 31 in the horizontal member is provided with a hand wheel 161, which 35 facilitates the starting of the machine by the operator who sits in front of the horizontal arm. When this hand wheel 161 is turned it not only rotates the shaft 31, but through the connecting links 32 and 33 40 will rotate the main shaft and start the same.

It is obvious that minor changes in the details of construction and arrangement of parts, particularly the position of the 45 needles, may be made without departing from the spirit of the invention as set forth in the appended claims.

Having thus described my invention, 50 what I claim as new and desire to secure by Letters Patent, is:

1. The combination of a standard, an overhanging arm carried thereby, a needle bar reciprocating in said overhanging arm, and a needle carried by said needle bar, an 55 arm projecting outwardly and upwardly from the standard, a depending arm supported by said last named arm, and a work supporting arm carried at the lower end of said depending arm and having its free end 60 extending underneath the free end of said overhanging arm.

2. The combination of a standard, an overhanging arm carried thereby, a needle bar reciprocating in said overhanging arm,

and a needle carried by said needle bar, an 65 arm projecting outwardly and upwardly from the standard, a depending arm supported by said last named arm, a work supporting arm carried at the lower end of said depending arm and having its free end extending underneath the free end of said 70 overhanging arm, a looper mounted in the free end of said work supporting arm, and means extending through said arms projecting from the standard for operating 75 said looper.

3. The combination of a standard, an overhanging arm carried thereby, a needle bar reciprocating in said overhanging arm, and a needle carried by said needle bar, an 80 arm projecting outwardly and upwardly from the standard, a depending arm supported by said last named arm, a work supporting arm carried at the lower end of said depending arm and having its free end 85 extending underneath the free end of said overhanging arm, a looper mounted in the free end of said work supporting arm, means extending through said arms projecting from the standard for operating 90 said looper, a feed dog carried by said work supporting arm and disposed so as to feed the work off from the end of the arm, and means extending through said arms supported by the standard for operating said 95 feed dog.

4. The combination of a standard, an overhanging arm carried by said standard, a needle bar reciprocating in said overhanging arm, and a needle carried by said needle 100 bar, an arm carried by the standard and projecting outwardly and upwardly therefrom, a horizontal arm parallel with the overhanging arm and carried by said arm projecting from the standard, a depending arm 105 carried by said horizontal arm at the free end thereof, and a work supporting arm carried at the lower end of said depending arm and having its free end extending underneath the free end of the overhanging 110 arm.

5. The combination of a standard, an overhanging arm carried by said standard, a needle bar reciprocating in said overhanging arm, and a needle carried by said needle 115 bar, an arm carried by the standard and projecting outwardly and upwardly therefrom, a horizontal arm parallel with the overhanging arm and carried by said arm projecting from the standard, a depending 120 arm carried by said horizontal arm at the free end thereof, a work supporting arm carried at the lower end of said depending arm and having its free end extending underneath the free end of the overhanging 125 arm, a looper mounted within the free end of said work supporting arm and co-operating with said needle, and means extending

through said arms supported by the standard for operating said looper.

6. The combination of a standard, an overhanging arm carried by said standard, 5 a needle bar reciprocating in said overhanging arm, and a needle carried by said needle bar, an arm carried by the standard and projecting outwardly and upwardly therefrom, a horizontal arm parallel with the 10 overhanging arm and carried by said arm projecting from the standard, a depending arm carried by said horizontal arm at the free end thereof, a work supporting arm carried at the lower end of said depending 15 arm and having its free end extending underneath the free end of the overhanging arm, a looper mounted within the free end of said work supporting arm and coöperating with said needle, means extending 20 through said arms supported by the standard for operating said looper, a feed dog at the free end of said work supporting arm arranged for feeding the material off from the arm, and means extending through 25 said arms supported by the standard for operating said feed dog.

7. The combination with a standard, an overhanging arm carried thereby, a needle bar reciprocating in said overhanging arm, 30 a needle mounted on said needle bar, an arm carried by said standard and projecting outwardly and upwardly therefrom, a horizontal arm carried at the outer free end of said projecting arm, a main shaft in said 35 standard, a shaft in said horizontal arm, and means for positively rotating the shaft in the horizontal arm from the shaft in the standard, an arm depending from the outer end of the horizontal arm, a work supporting arm carried at the lower end of said 40 depending arm and having its free end extending underneath the free end of the overhanging arm, complemental stitch forming mechanism located within said work supporting arm, and means for operating the 45 same from said rotating shaft in the horizontal arm.

8. The combination with a standard, an overhanging arm carried thereby, a needle 0 bar reciprocating in said overhanging arm, a needle mounted on said needle bar, an arm carried by said standard and projecting outwardly and upwardly therefrom, a horizontal arm carried at the outer free end of 5 said projecting arm, a main shaft in said standard, a shaft in said horizontal arm, and means for positively rotating the shaft in the horizontal arm from the shaft in the standard, an arm depending from the outer 10 end of the horizontal arm, a work supporting arm carried at the lower end of said depending arm and having its free end extending underneath the free end of the overhanging arm, complemental stitch forming

mechanism located within said work supporting arm, means for operating the same from said rotating shaft in the horizontal arm, a feed dog at the free end of said work supporting arm, and means for operating said feed dog from said rotating shaft in 70 the horizontal arm.

9. The combination with a standard, an overhanging arm carried thereby, a needle bar reciprocating in said overhanging arm, needles mounted on said needle bar, an arm 75 carried by said standard and projecting outwardly and upwardly therefrom, a horizontal arm carried at the outer free end of said projecting arm, a main shaft in said standard, a shaft in said horizontal 80 arm, and means for positively rotating the shaft in the horizontal arm from the shaft in the standard, an arm depending from the outer end of the horizontal arm, a work supporting arm carried at the lower end of 85 said depending arm and having its free end extending underneath the free end of the overhanging arm, complemental stitch forming mechanism located within said work supporting arm, means for operating 90 the same from said rotating shaft in the horizontal arm, a main feed dog at the free end of said work supporting arm, means for operating said main feed dog from said rotating shaft, an auxiliary feed 95 dog at the free end of said work supporting arm, and means for giving said auxiliary feed dog a differential feeding movement.

10. The combination with a standard, an overhanging arm carried thereby, a needle bar reciprocating in said overhanging arm, needles mounted on said needle bar, an arm carried by said standard and projecting outwardly and upwardly therefrom, a horizontal arm carried at the outer free end of said projecting arm, a main shaft in said standard, a shaft in said horizontal arm and means for positively rotating the shaft in the horizontal arm from the shaft 100 in the standard, an arm depending from the outer end of the horizontal arm, a work supporting arm carried at the lower end of said depending arm and having its free end extending underneath the free end of 105 the overhanging arm, complemental stitch forming mechanism located within said work supporting arm, means for operating the same from said rotating shaft in the horizontal arm, a main feed dog at the free 110 end of said work supporting arm, means for operating said main feed dog from said rotating shaft, an auxiliary feed dog at the free end of said work supporting arm, and means for giving said auxiliary feed dog 115 a differential feeding movement, said means for operating the auxiliary feed dog being adjustable at the will of the operator,

whereby the differential throw of said feed dog may be varied.

11. The combination with a standard, an overhanging arm carried thereby, a needle bar reciprocating in said overhanging arm, two pairs of spaced needles carried by said needle bar, one pair being arranged in rear of the other, a work supporting arm extending in a direction at right angles to the plane of the overhanging arm and having its free end underneath the free end of the overhanging arm, means for suspending said work supporting arm, whereby there is a free space underneath and at the sides of the same from end to end thereof, a looper shaft extending longitudinally of said work supporting arm, two loopers on said shaft, one for each pair of needles, and means operating through said suspending means for oscillating said looper shaft.

12. The combination with a standard, an overhanging arm carried thereby, a needle bar reciprocating in said overhanging arm, two pairs of spaced needles carried by said needle bar, one pair being arranged in rear of the other, a work supporting arm extending in a direction at right angles to the plane of the overhanging arm and having its free end underneath the free end of the overhanging arm, means for suspending said work supporting arm, whereby there is a free space underneath and at the sides of the same from end to end thereof, a looper shaft extending longitudinally of said work supporting arm, two loopers on said shaft, one for each pair of needles, means operating through said suspending means for oscillating said looper shaft, a main feed dog, a feed bar located within said work supporting arm, and supporting said feed dog, and means operating through said suspending means for actuating the feed bar.

13. The combination with a standard, an overhanging arm carried thereby, a needle bar reciprocating in said overhanging arm, two pairs of spaced needles carried by said needle bar, one pair being arranged in rear of the other, a work supporting arm extending in a direction at right angles to the plane of the overhanging arm and having its free end underneath the free end of the overhanging arm, means for suspending said work supporting arm, whereby there is a free space underneath and at the sides of the same from end to end thereof, a looper shaft extending longitudinally of said work supporting arm, two loopers on said shaft, one for each pair of needles, means operating through said suspending means for oscillating said looper shaft, a main feed dog, a feed bar located within said work supporting arm, and supporting said feed dog, means operating through said suspending means for actuating the

feed bar, an auxiliary feed dog at the free end of said work supporting arm, and means for giving said auxiliary feed dog a differential movement from the feed bar of the main feed dog.

14. The combination of a standard, an overhanging arm carried by said standard, a needle bar reciprocating in the outer end of said work supporting arm, two pairs of spaced needles, one pair being arranged in rear of the other and carried by said needle bar, a work supporting arm located in a line at right angles to the plane of the overhanging arm, means for suspending said work supporting arm, whereby there is a free space underneath the sides thereof from end to end of said work supporting arm, complementary stitch forming mechanism located within said work supporting arm, feeding mechanism carried by said work supporting arm, trimming mechanism located in front of said needles and including a movable trimming blade operating in a horizontal plane for preparing the edges of the fabric to be stitched by the needles.

15. The combination of a standard, an overhanging arm carried by said standard, a needle bar reciprocating in the outer end of said work supporting arm, two pairs of spaced needles, one pair being arranged in rear of the other and carried by said needle bar, a work supporting arm located in a line at right angles to the plane of the overhanging arm, means for suspending said work supporting arm, whereby there is a free space underneath the side thereof from end to end of said work supporting arm, complementary stitch forming mechanism located within said work supporting arm, feeding mechanism carried by said work supporting arm, trimming mechanism located in front of said needles and including a movable trimming blade operating in a horizontal plane for preparing the edges of the fabric to be stitched by the needles, a presser foot, and a deflector carried by the presser foot for guiding the trimmed off strip away from the needles.

16. A sewing machine, including in combination, two pairs of spaced needles, a threaded looper for each pair of needles, one pair of needles being arranged in rear of the other pair, the needles of one pair being offset relative to the needles of the other pair and thread laying devices for each pair of needles, said pairs of needles being so disposed that the loops in the looper thread of the looper cooperating with the rear pair of needles overlie the loops formed in the looper thread by the looper cooperating with front pair of needles.

17. A sewing machine including in combination, two pairs of spaced needles, a looper for each pair of needles, one pair of needles being arranged in rear of the other, the needles of one pair being offset relative to

- to the needles of the other pair, thread laying devices for each pair of needles, said thread laying devices including an oscillating arm movable in a direction substantially parallel to the line of feed, two independent thread guides mounted on said arm and carrying thread for the respective sets of needles, a second oscillating arm having two thread hooks movable in a direction substantially at right angles to the line of feed, one thread hook being located in front of both sets of needles and the other thread hook being located and operating between the sets of needles.
18. A sewing machine including in combination, two pairs of spaced needles, a looper for each pair of needles, one pair of needles being arranged in rear of the other, the needles of one pair being offset relative to the needles of the other pair, thread laying devices for each set of needles and a feeding mechanism including a feed dog extending from in front of the front pair of needles to the rear of the rear pair of needles.
19. A sewing machine including in combination, two pairs of spaced needles, a looper for each pair of needles, one pair of needles being arranged in rear of the other, the needles of one pair being offset relative to the needles of the other pair, thread laying devices for each set of needles and a feeding mechanism including a feed dog extending from in front of the front pair of needles to the rear of the rear pair of needles, and an auxiliary feed dog arranged in front of the front pair of needles and mechanism for giving said auxiliary feed dog a differential movement relative to the main feed dog.
20. A sewing machine including in combination, two pairs of spaced needles, a looper for each pair of needles, one pair of needles being arranged in rear of the other, the needles of one pair being offset relative to the needles of the other pair, thread laying devices for each set of needles and a feeding mechanism including a feed dog extending from in front of the front pair of needles to the rear of the rear pair of needles, said feed dog also having feed sections extending on opposite sides of said needles.
21. A sewing machine including in combination, two pairs of spaced needles, a looper for each pair of needles, one pair of needles being arranged in rear of the other, thread laying devices for each pair of needles, means for oscillating said thread laying devices including devices whereby said thread laying devices may be disconnected from their operating means and moved laterally to one side to give access to the needles.
22. A sewing machine including in combination, a work support, a pair of spaced needles, a looper coöperating with the needles, a thread laying device coöperating with the needles above the work support, means for oscillating said thread laying device, said means including devices whereby said thread laying device may be disconnected from its oscillating means and moved laterally to one side to give access to the needles.
23. The combination of pairs of spaced needles arranged one in advance of the other, a looper for each pair of needles, an oscillating shaft, a looper carrier mounted on the end of said shaft and supporting one of said loopers, a second looper carrier detachably connected to the first looper carrier and supporting the other looper.
24. The combination of pairs of spaced needles arranged one in advance of the other, a looper for each pair of needles, an oscillating shaft, a looper carrier mounted on the end of said shaft and supporting one of said loopers, a second looper carrier detachably connected to the first looper carrier and supporting the other looper, said first named looper carrier having a clearance space for the needles.
25. A sewing machine including in combination, a standard, an overhanging arm supported thereby, a needle mounted to reciprocate on said overhanging arm, a work support including a horizontally disposed arm, a work supporting arm suspended therefrom and having its free end underneath the overhanging arm, complementary stitch forming mechanism at the free end of said work supporting arm, a rotating shaft mounted in said horizontally disposed arm and connections between the same and said complementary stitch forming mechanism and a hand wheel attached to said shaft.
26. A sewing machine including in combination, a standard, an overhanging arm, a needle mounted to reciprocate on said overhanging arm, a main shaft in said standard, devices for reciprocating said needle from said shaft, a work support carried by said standard, said work support including a horizontally disposed arm, a work supporting arm mounted on said horizontal arm and having its free end underneath the free end of the overhanging arm, a complementary stitch forming mechanism in the work supporting arm, a rotating shaft in said horizontally disposed arm, means for rotating said shaft from the main shaft, means for operating said complementary stitch forming mechanism from said shaft in the horizontally disposed arm and a hand wheel attached to said last named shaft whereby the main shaft may be started or turned at the will of the operator.
27. A sewing machine including in com-

- bination, a work support, feeding mechanism, a presser foot, trimming mechanism and a stitching mechanism including two sets of needles arranged one behind the other, one needle of one set being disposed in a plane extending between the needles of the other set and substantially parallel with the line of feed, said presser foot having a fabric guiding channel extending in a plane 10 passing centrally between the outer needles of said set of needles, said trimming mechanism having a trimming blade arranged to trim the edges of the fabric, projecting upwardly through said fabric guiding channel.
- 15 28. A sewing machine including in combination, a work support, a pair of widely spaced needles, a pair of closely spaced needles located in rear of the widely spaced needles, and a thread carrying looper co-operating with each pair of needles, said closely spaced needles being disposed relatively to the widely spaced needles so that the loops formed in the looper thread of the looper co-operating with the closely spaced 20 needles will overlie the loops formed in the looper thread of the looper co-operating with the widely spaced needles.
- 25 29. A sewing machine including in combination, a work support, a pair of widely spaced needles, a pair of closely spaced needles located in rear of the widely spaced needles, a thread carrying looper co-operating with each pair of needles, and a loop retainer co-operating with the looper of the closely spaced needles, said closely spaced needles being disposed relatively to the widely spaced needles so that the loops formed in the looper thread of the looper co-operating with the closely spaced needles will overlie the loops formed in the looper thread of the looper co-operating with the widely spaced needles.
- 30 35 40 45 50

spaced needles, a pair of closely spaced needles located in rear of the widely spaced needles, a thread carrying looper co-operating with each pair of needles, and a loop retainer co-operating with the looper of the closely spaced needles, said closely spaced needles being disposed relatively to the widely spaced needles so that the loops formed in the looper thread of the looper co-operating with the closely spaced needles will overlie the loops formed in the looper thread of the looper co-operating with the widely spaced needles.

30. A sewing machine including in combination, a work support, a pair of widely spaced needles, a pair of closely spaced needles located in rear of the widely spaced needles, a thread carrying looper co-operating with each pair of needles, and a loop retainer co-operating with the looper of the closely spaced needles, and a thread laying device co-operating with each pair of needles above the work support.

In testimony whereof, I affix my signature in the presence of two witnesses.
